R. GREENHAM

WATER HEATING AND CIRCULATING DEVICE

Filed May 26, 1920

Inventor
Richard Greenham.

Chas E Townsend.

By

His Atty.

UNITED STATES PATENT OFFICE.

RICHARD GREENHAM, OF SAN FRANCISCO, CALIFORNIA.

WATER HEATING AND CIRCULATING DEVICE.

Application filed May 26, 1920. Serial No. 384,273.

To all whom it may concern:

Be it known that I, RICHARD GREENHAM, a citizen of the United States, residing at the city and county of San Francisco and 5 State of California, have invented a new and useful Improvement in Water Heating and Circulating Devices, of which the following is a specification.

This invention relates to a water heating and circulating device, and especially to a thermo-siphon actuated circulating system whereby hot water may be delivered to points considerably below the level of a heater and maintained in constant circulation 10 by thermo-siphon action.

It is well known that most hot water heating and circulating systems employed today operate on the thermo-siphon principle, that is water within a coil or 15 like heating device will expand and travel in an upward direction when subjected to heat, thus starting a circulation of the water which continues as long as heat is applied. Hot water radiators and like devices 20 are often operated on this principle and are efficient and satisfactory in operation as long as they are located at a point above the heater. They however become, 25 practically speaking, inoperable when located on an approximate level with the heater as it is difficult to maintain thermo-siphon circulation through the same at this point and they become altogether useless and inoperable if placed even a foot or so 30 below the heater. This is obviously a great drawback as it renders it almost impossible to operate radiators on the same floor as that on which the heater is located; this being due to the fact that the radiators as 35 a rule are placed directly on the floor and the heater above the same to make room for a fire box, burners, etc.

One of the objects of the present invention is to provide a water heating and circulating device which operates on the thermo-siphon principle, but is capable of delivering hot water to points several feet below the heater, and simultaneously maintains the water thus delivered in constant 45 circulation, thus rendering it possible to efficiently operate radiators whether placed on a level with the heater or when placed a considerable distance below the same.

Further objects will hereinafter appear. 50 The invention consists of the parts and the construction, combination and arrange-

ment of parts as hereinafter more fully described and claimed, having reference to the accompanying drawing, in which the figure is a diagrammatic view showing the 60 piping system and the circulating device.

Referring to the drawing in detail, A indicates a suitable form of heater, consisting of a stove or the like, in which is mounted a burner and a coil 2. 3 indicates an ordinary hot water kitchen tank, 4 the service pipe, through which cold water is admitted from a source of supply, 5 the outgoing hot water service pipe, 6 the hot water intake connection, and 7 the cold 65 water outlet. This is connected by a pipe 8 with the lower part of the heating coil 2, while the upper end of the heating coil 2 is connected with a circulating device, generally indicated at B. This device 70 consists of an exterior stand pipe 9 and an interior pipe 10, the inner pipe being of such a diameter that a surrounding annular passage 11 is formed, through which the hot water discharging from the coil 2 will circulate. The pipe 10 is connected with the hot water intake connection 6 and extends 75 downwardly through the exterior pipe 9 and terminates near the bottom thereof. The lower end of the pipe 10 is open and water 80 is admitted thereto from the annular passage 11. The lower end of the pipe 9 is closed by a cap or a similar device 12, and the upper end by means of an elbow 13 and a plug 14. The hot water inlet connection 6 passes through said plug and is connected 85 with the pipe 10 by means of an elbow 15. The upper end of the heating coil is connected with the exterior pipe 9 by means of a T-connection 16, and a circulating pipe 90 95 17 is employed which terminates above and below the T-connection 16, as will herein-after be described.

In actual operation with a fire started under the coil 2, it can readily be seen that 100 the water heated in the coil 2 will rise upwardly through the same and will discharge through the T-connection 16 into the annular chamber 11. The hot water will rise in the annular chamber and will for a short period circulate upwardly through the annular chamber and then downwardly through the pipe 17 and again enter the annular chamber. This circulation will 105 take place until the upper portion of the pipe 10 becomes heated. Heating of this pipe will cause the water contained therein 110

to rise upwardly and discharge into the tank 3, and a downward flow of hot water through the annular chamber 11 will then commence as an upward flow of water in the pipe 10 will naturally have to be replaced by water from the annular passage. The hot water entering the tank through the connection 6 collects in the upper portion thereof in the usual manner and may be drawn off through the pipe 5, any water drawn through this pipe being automatically replaced from the main cold water service pipe 4. Water is at the same time constantly entering the lower portion of the heating coil 2 and circulation is therefore maintained so that all the water will gradually increase in temperature.

The important feature of the present invention is the fact that the hot water discharging from the heating coil 2 first serves the function of heating the inner pipe 10, thus causing an upward flow of water through the same, and as this upward flow of water has to be replaced, it is obvious that the hot water discharging from the coil 2 will flow downwardly through the annular passage and then upwardly through the pipe 10. Hot water is in this manner delivered to a point considerably below the heater.

In actual practice I have carried circulation to a point approximately ten feet below the heater proper, and as far as I know circulation might be carried downwardly a considerably greater distance.

From the foregoing it can be seen that the hot water discharging from the coil 2 will flow downwardly through the annular passage, due to the thermo-siphon action in the pipe 10. The circulating device comprising the pipes 9 and 10 is therefore at all times filled with hot water and if it is desired to supply a radiator, or to otherwise employ the hot water, it is only necessary to tap the exterior pipe as shown at 19. The tap connection should be made above the lower end of the pipe 10. Hot water thus withdrawn may be directed to a radiator such as indicated at 20, and the return connection therefrom may be made directly with the lower end of the circulating device as by means of a pipe 21, circulation through the radiator being of course regulated by a valve 22, or other suitable means.

In the present drawing I have illustrated the heater A and main circulating tank 3 as

located on one floor, and the radiator 20 on the floor below the same, this being done to illustrate the possibilities of the present invention.

While the apparatus here illustrated is specifically employed for circulation of hot water, it is obvious that it may be employed for other purposes, for instance, for the circulation of other liquids and fluids, and I similarly wish it understood that various changes in design and construction may be resorted to within the scope of the appended claims, also that the materials and finish of the several parts employed may be such as the experience and judgment of the manufacturer may dictate or varying conditions may demand.

Having thus described my invention, what I claim and desire to secure by Letters Patent is—

1. A water heating and circulating device comprising a heater, a stand pipe, a receptacle, a tube in the stand pipe connected at one end with the receptacle and having its lower end open and terminating in the lower end of the stand pipe, means for delivering hot water from the heater to the upper portion of the stand pipe to heat the upper portion of the tube extending therethrough so as to start a thermosiphon flow through said tube, and a return connection between the receptacle and the lower portion of the heater.

2. A liquid heating and circulating apparatus comprising a heater and a receptacle, an interposed circulating device including a stand-pipe, an inlet pipe connecting the upper end of the stand-pipe with the heater, a tube extending through the stand-pipe and connected at its upper end with the receptacle and open at its lower end to communicate with the interior lower end of the stand-pipe, a radiator, a pair of pipes connecting the radiator with the lower end of the stand-pipe, one forming a feed and the other a return connection, and a pipe connection between the lower part of the receptacle and the heater.

In testimony whereof I have hereunto set my hand in the presence of two subscribing witnesses.

RICHARD GREENHAM.
